PORTABLE LEAN-TO SCAFFOLDS
Fred P. Fedoryk, 71 Eg St., Central Islip,
Long Island, N.Y.
Filed Nov. 1, 1963, Ser. No. 320,764
1 Claim. (Cl. 182—230)

The present invention relates to improvements in scaffolds such as are used for finishing, painting or repairing outside walls of buildings and, more specifically, it relates to a new and improved scaffold of the lean-to type which is particularly well adapted for use in connection with two or three story structures.

One object of the present invention is the provision of a device of the character described which is light in weight, quickly installed and dismantled, safe and sturdy in use, and comparatively inexpensive to manufacture.

Another object of the present invention is the provision of a device of the character described which is adjustable, while for its installation does not require any appreciable amount of skill or effort, which can be used on foundation walls or other walls without finish to which other scaffolds cannot be fastened, and which also is reliable in use and well adapted for withstanding the rough usage to which devices of this type ordinarily are subjected.

With the foregoing and other objects which will appear as the description proceeds, the invention consists of certain novel details of construction and combinations of parts hereinafter more fully described and pointed out in the claim, it being understood that changes may be made in the construction and arrangements of parts of the embodiment disclosed without departing from the spirit of the invention as claimed.

In the accompanying drawing I have set forth an illustrative embodiment of my invention.

In said drawing:

FIGURE 1 is a front elevation of a preferred embodiment of my invention;

FIG. 2 is a side elevation; and,

FIG. 3 is a fractional, enlarged sectional view on the line 3—3 of FIG. 2.

Similar reference characters refer to similar parts throughout the several views.

In FIGS. 1 and 2 of the drawing a wall 1 and a floor surface 2 are indicated by dash-and-dotted lines. My new and improved scaffold consists primarily of a pair of lean-to posts 3, on each of which is mounted a bracket member 4 that carries one or more platform blanks or boards 5. The posts 3 are leaned against the wall 1, at an angle of about thirty degrees, and they are preferably supported at the bottom by flat base plates or blanks 7 for the purpose of preventing the posts 3 from sinking into a soft surface. The upper ends of the posts 3 preferably are provided with rubber bumpers 10 or the like for preventing the device from marring finished wall surfaces.

While the elements 3 and 4 can be made of wood, for instance the posts 3 of lumber being two by eight inches in cross-section, I prefer to make them of moulded steel or aluminum bars of a triple-U-shaped formation, as shown in FIG. 3, having channels 11, 12 and 15. I also prefer to make the bracket 4 of metal parts 17, 20 and 21. The member 17, which I prefer to call a bracket base member, preferably is U-shaped in cross-section and has a web portion that is adjustably secured to the web portion of the channel 12 by means of one or more screws 22, that are extended through one or more holes 23 of a row of holes 23 in the channel portion 12 of the post 3. The flange portions of the U-shaped member 17 have holes 24 and 25 in opposite sections, and the lower end

2

of the brace member 20 is pivotably secured to the member 17 by means of a bolt 27 extending therethrough as well as through a pair of opposite holes 25.

The upper end of the brace member 20 which may be 5 bi-furcated as shown, is pivotally connected to one end of the horizontal member 21 at 27, and the other end of the member 20 is pivotally connected to the upper portion of the member 17 by means of a bolt 30 (FIG. 27) extending therethrough as well as through a pair of opposite holes 24. This arrangement allows an adjustment of 10 the angle 31, so that the platform 5 always can be maintained in a level position, irrespective of whether or not the posts are disposed to the wall 1 at thirty degrees or at another angle of inclination.

I have found that the most preferable main dimensions for my device are a length of seven feet of each of the posts 3, a distance of twelve inches from the upper ends of the posts 3 to the bolt 30, and a horizontal distance of twelve inches from the bolt 30 to the pivot point 20 27.

Since certain changes may be made in the above article and different embodiments of the invention could be made without departing from the scope thereof, it is intended that all matter contained in the above description or 25 shown in the accompanying drawing shall be interpreted as illustrative and not in a limiting sense.

It is also to be understood that the following claim is intended to cover all of the generic and specific features of the invention herein described, and all statements of the scope of the invention which as a matter of language might be said to fall therebetween.

Having thus fully described my said invention, what I claim as new and desire to secure by Letters Patent is:

30 A portable lean-to scaffold comprising a pair of upwardly inclined posts of a triple U-shaped cross-sectional formation having each a first longitudinal groove with a perforated web portion on one web side and a pair of second longitudinal grooves on the other side, a pair of 40 longitudinal bracket base members having upper and lower portions and being of cross-sectional U-shaped formation each having a perforated web portion adjacent the inner side of the web portion of the first longitudinal groove of a post and having also flange portions protruding beyond the first longitudinal groove of each post, a screw extending through the web portions of said bracket base member and of said first longitudinal groove of each post, a horizontal member having one of its ends adjustably and pivotably mounted on the upper end portion 50 of the flange portions of each bracket base member, an upwardly inclined brace member having an upper extremity pivotably secured to the other end of each horizontal member and having its lower extremity pivotably and 55 adjustably secured to the lower flange portions of the base member, and a horizontal platform member supported by said horizontal members.
